UNITED STATES PATENT OFFICE.

WILLIAM FRANCIS DONER, OF WINNIPEG, MANITOBA, CANADA.

ROTARY ENGINE.

1,077,874.

Specification of Letters Patent.

Patented Nov. 4, 1913.

Application filed December 2, 1911. Serial No. 868,536.

To all whom it may concern:

Be it known that I, WILLIAM FRANCIS DONER, of the city of Winnipeg, in the Province of Manitoba, Canada, have invented certain new and useful Improvements in Rotary Engines, of which the following is the specification.

My invention relates to a rotary engine, and the object of the invention is to provide a simply constructed, efficient, and durable engine in which there are few parts so that it does not get out of working order readily.

A further object of the invention is to construct the engine so that the rotating part carries no movable members, thereby preserving at all times during the rotation an even balance around the center of rotation.

With the above objects in view the invention consists essentially in the arrangement and construction of parts hereinafter more particularly described, reference being had to the accompanying drawing in which—

Figure 1 is a side elevation of the complete machine. Fig. 2 is a sectional view centrally through the same, the section being taken in the plane denoted by the line X'X', Fig. 3. Fig. 3 is a side elevation of the engine with one of the side plates removed. Fig. 4 is an enlarged detailed vertical sectional view through one of the pistons.

In the drawings like characters of reference indicate corresponding parts in each figure.

1 and 2 represent side plates supplied at the bottom with foot pieces 3 and 4 and cast with the cylinder forming members 5, and 40 6, which, when brought together, inclose the piston chamber 7. The piston chamber is circular and has a shaft 8 passing centrally through it, which shaft is supported in suitable bearings formed in side arm 9 (in the 45 form of spokes) formed as part of the plates 1 and 2. These arms radiate between the shaft and the cylinder forming members 5 and 6.

10 is a circular disk fixed on the shaft 8 and passes rotatably between the members 5 and 6, and provided with projecting pieces 11 spaced at suitable intervals which pass into the piston chamber 7.

12 are pistons supplied each with a pair of 55 extending jugs 13 which are bolted permanently to the projecting pieces 11. The pis-

tons are designed to fit snugly within the cylinder formed by the members 5 and 6 and are each constructed of two parts, a back cup-shaped member 14 and a front disk 15, the disk being held to the cup-shaped member by a spring 16.

17 are wearing, split rings slipped on to the cup-shaped member 14 and having their outer faces bearing against the walls of the 65 piston chamber. The edges of the disks 15 are beveled at 15', and the adjoining faces of the rings 17 are beveled out at 17' to receive them.

The above piston construction is such that 70 the disks will have a tendency to spread the rings against the chamber walls and form a tight joint upon the charge being ignited within the piston chamber as later described.

18 and 19 are two circular plates centered 75 on the shaft and bolted to each other through the disk 10. The plates are supplied with outwardly directed flanges 20 which serve to break the joint formed between the disk and the plates 1 and 2 and 80 carry pins 21 for a purpose later described.

22 represent spark plugs screwed into the cylinder forming member 5 and opening to the piston chamber as is usual.

23 are trip bars slidably mounted in the 85 arms 9 and having their upper ends connected with the spark plugs, and their lower ends engageable with the successive pins 21 upon the shaft being rotated. The lower ends of the trip bars are cut at an incline so 90 that they will be raised by the pins 21 as the pins pass them. Spiral springs 24 tie the trip bars to the arms so that they are continuously pressed toward the shaft 8.

I have not enlarged upon the construction 95 of the spark plugs as any form of plug could be used which will allow the contact to be made and broken by the action of the trip bars 23.

25 are gates of greater width than the 100 piston chamber, which gates are slidable in grooves 26 formed in the cylinder forming members 5 and 6 as well as in the guide plates 27 which extend outwardly from the plates 1 and 2. It is to be noticed also that 105 the wall of the piston chamber is grooved across at 28 to receive the lower edge of the gates when they are in their inner positions. On account of this construction there is no 110 possibility of leakage past the gates once they are closed across the piston chamber.

29 are bell cranks pivotally mounted on

suitable pins 30 passing between the guide plates 27. The gates are connected to the bell cranks at one end and actuating bars 31 are fastened to the opposite ends and 5 pass into the piston chamber through suitable openings formed at 32 in the walls thereof. These bars 31 are engaged by the passing projecting pieces 11 thus rocking the crank arm 29 on its pivot and forcing 10 the gate 25 downwardly to tightly closed position. By means of this construction positive means are provided for assisting the springs 33 to perform their function of normally holding the gates closed. Spiral 15 springs 33 are secured to the bell cranks and to the plate 6, which springs tend to hold the gates within the piston chamber.

34 are inlet ports, and 35 exhaust ports passing through the walls of the chamber. 20 The ports 34 are connected up with any suitable source of gas supply, such as mixed gasolene and air, while those 35 are connected up with suitable exhaust pipes.

The operation of the engine is now described assuming that the shaft is primarily rotated and the charges drawn into the piston chambers through the ports 34 and also that the ports are in the positions shown in Fig. 3 of the drawing. There will be a 25 charge in the piston chamber at the points "A, B, C, and D", between the respective gates 25 and the adjoining piston. These charges will be ignited and exploded by the action of the trip bars on the spark 30 plugs at set periods, so that the pistons will be forced in the direction indicated by the arrow, Fig. 3, as it is to be remembered the gates are at this time stationary and in 35 their inner position. This will cause the shaft to rotate as the pistons are carried by the disk 10. The exploded gases expanding force the pistons past the bars 31 until they 40 reach, respectively, the adjoining gates when the inclined edges 11' of the projecting pieces 11 will pass under such gates and 45 raise them. The spent charges escape through the exhaust ports as soon as the respective pistons pass the ports.

What I claim as my invention is:

50 1. The combination comprising, a suitably supported rotatable shaft, a circular disk mounted on the shaft and supplied at its edge with projecting pieces having each an inclined edge, pistons permanently secured to the projecting pieces, connected

plates forming an annular piston chamber adapted to receive the pistons, such piston chamber being supplied with suitably located inlet and outlet ports and being fitted with conveniently located spark plugs, 55 spring pressed normally closed gates passing across the piston chamber and located at set distances apart, said gates, when closed, having their inner ends and edges received within grooves formed in the side 60 plates, pivoted bell cranks connected to the outer ends of the gates and actuating bars carried by the bell cranks and entering the piston chamber, said actuating bars being arranged to engage with the inclined edges 65 of the projecting pieces to positively close the gates, as and for the purpose specified.

2. In a rotary engine, the combination with a suitably supported rotatable shaft, of a circular disk fixed on the shaft and 70 having suitably spaced projecting pieces extending from the edge thereof, and pistons permanently secured to the projecting pieces, said pistons comprising each a rear cup-shaped member, a split ring fitted on to 75 the same and extending there beyond, and having its forward edge tapered, a disk having a tapering edge engageable with the tapered edge of the ring and a flat spring connecting the disk with the cup-shaped 80 member, as and for the purpose specified.

3. The combination comprising, a suitably supported rotatable central shaft, a disk fixed on the shaft, pistons located on the periphery of the disk and placed at suitable intervals, a pair of circular plates centered on the shaft on either side of the disk, 90 said plates having their peripheral edges bent in opposite directions, connected side plates forming a piston chamber and receiving the pistons and admitting the edge of the disk, said piston chamber being supplied with suitable inlet and outlet ports, spark plugs, located at suitable intervals in the wall of the piston chamber, slideable gates 95 arranged at intervals around the piston chamber and designed to pass across the piston chamber, and means for operating the gates, as and for the purpose specified.

Signed at Winnipeg, in the province of 105 Manitoba, this 17th day of June, 1911.

WILLIAM FRANCIS DONER.
